WRINGER CONTROL

Floyd S. Wheeler, Arlington, Va., assignor to Westinghouse Electric & Manufacturing Company, East Pittsburgh, Pa., a corporation of Pennsylvania

Application September 10, 1937, Serial No. 163,194

12 Claims. (Cl. 74—387)

My invention relates to power-driven wringers and more particularly to the control of the reversing mechanism and the locking device for such wringers.

5 With those wringers now known to the art, it is customary to mount them upon supporting means in such a manner that the wringer may be adjusted or swung into a plurality of working positions about a vertical axis which is usually 10 the wringer drive shaft. It is necessary to lock such wringers to prevent them from rotating about the vertical axis when such wringers are connected to the wringer drive shafts. If the wringer should not be locked while having a working 15 connection with the drive shaft, such wringer is liable, while under load, to swing about the vertical axis and seriously injure an operator.

It is, therefore, an object of my invention to provide a locking device which cannot be unlocked 20 when the wringer rolls are operatively connected with the power shaft.

To prevent the wringer swinging about the vertical axis, it has been necessary with most wringers known to the art to use two handles or 25 controls, one to regulate the transmission between the wringer rolls and the power shaft and the second to regulate the locking device. With such wringers it is possible for the operator to accidentally disconnect the locking device while 30 the wringer is under load, under which circumstances the wringer would rotate about the vertical axis and cause serious injury to the operator if she were struck by such rotating wringer.

With those wringers having a single handle to 35 control both the transmission and the locking device, it has been necessary to have the locking device unlocked while the transmission has been in a neutral position. This requires the wringer to be very accurately lined up with a locking plate 40 to permit the cooperation of the locking device therewith before the wringer can be operatively associated with the power shaft.

It is, therefore, a further object of my invention to provide a single-handle controlling device 45 which will selectively operate either the transmission or the locking device, only when the transmission is in a neutral position, and will permit the handle and the transmission to be in a neutral position without unlocking the locking 50 device.

A further object of my invention is to provide a wringer control mechanism which will be simple to operate and inexpensive to manufacture and which will be fool-proof and positive in 55 action.

Other objects of my invention will either be pointed out specifically in the course of the following description of a device embodying my invention, or will be apparent from such description. 5

In the accompanying drawings:

Figure 1 is an elevational view partly in section of a wringer embodying my invention;

Fig. 2 is a partial end elevational view of the wringer, with the control mechanism in one of its operative positions;

Fig. 3 is a partial sectional view taken along line III—III of Fig. 5;

Fig. 4 is an enlarged sectional view of the device shown in Fig. 1; 15

Fig. 5 is a partial sectional view similar to Fig. 4, with the control mechanism in one of its operative positions;

Fig. 6 is a partial sectional view taken along the line VI—VI of Fig. 4; 20

Fig. 7 is a partial sectional view similar to Fig. 3, but with the operative mechanism in a second operative position, as shown in Fig. 5;

Fig. 8 is a partial sectional view of a modified form of a portion of the operating mechanism 25 embodying my invention;

Fig. 9 is a sectional view taken along line IX—IX of Fig. 8, with the operating mechanism in one of its operative positions;

Fig. 10 is a sectional view similar to Fig. 9 with 30 the operating mechanism in a second operating position; and

Fig. 11 is a partial sectional view similar to Fig. 4, showing a modification of the control mechanism. 35

Referring to the accompanying drawings, I show a wringer 11 having a housing 12 with rolls 13 and 14 therein, a transmission housing or head 15 having a suitable reversing transmission 16 therein, a control mechanism 17, a locking device 18 and a power shaft 19 operatively associated with the transmission 16. 40

The wringer rolls 13 and 14 are movably and rotatably supported within the wringer housing 12 in any suitable manner and are driven through 45 a shaft 27 which may be operatively associated with the driven gear 29 by means of any suitable coupling means 28. As my invention will work equally well with any wringer structure, the exact method of construction and operation of the 50 wringer rolls and of a pressure device therefor are not shown.

The transmission gearing 16 located within the transmission housing or head 15 may comprise a well-known reversing mechanism such as driven 55

gear 29 and driving pinions 33 and 34. The pinions 33 and 34 may be rotatably mounted upon the drive shaft 19 which may be rotatably journaled within the sleeve 30 and the depending hollow boss 31, both of which may be an integral part of the housing 15. A suitable clutching member 32 may be splined to the shaft 19 and may have teeth or protruding portions 36 to operatively engage the corresponding slotted or notched portions 39 of the pinions 33 and 34, respectively.

The control mechanism 17 may comprise a bell crank operating lever 40 and a stub shaft 43. The bell crank operating lever 40 has one leg thereof (41) which extends outside the transmission housing, and such leg is used as the operating handle for the control mechanism. The second member of the bell crank operating lever 40 may be the finger 42 which extends within the stub shaft 43 as hereinafter described. The stub shaft 43 has associated therewith an annular grooved portion 44, a shoulder portion 45 and an irregularly slotted portion 46 located within the stub shaft 43. The irregularly slotted portion 46 comprises a main slotted portion 47 and a tapered slotted portion 48. The main slotted portion 47 extends through the stub shaft 43 and within the shoulder portion 45, and is of such a shape that it will readily permit the access and free operation of the finger portion 42 of the bell crank lever 40 therein. The bell crank operating lever 40 may be swingably mounted within the stub shaft 43 by means of a pin 49. The operating handle portion 41 will then be vertical while the finger portion 42 will be horizontally supported within the stub shaft 43.

A pin 37 may be eccentrically mounted upon the shoulder portion 45 of the stub shaft 43 and may be operatively associated with clutch member 32, by being engaged within an annular groove 35 located within such clutch member. A loosely fitting sleeve 38 may be placed over the pin 37 to act as a bearing between such pin and the clutch member 32.

The locking device 18 comprises a yoke member 50 and a locking pin 51. The yoke member 50 may have a lip portion 54 and a shoulder 55 located on the inner portion thereof. The locking pin 51 may be removably attached to the yoke member 50 by means of a cotter pin 52 and may be biased downwardly by the resilient spring member 53 which may operate between a portion of the housing 15 and a shoulder 56 located on the pin 51. The locking pin 51 may have a tapered snout 57 on the end thereof to facilitate such locking pin in cooperating with a locking plate 25 which may be rigidly attached to a washing tub 24 by means of support 26, or in any other suitable manner.

The yoke member 50 of the locking device 18 may be mounted within the annular notch 44 of stub shaft 43. With the operating lever 40 and yoke member 50 mounted as hereinabove described, the finger 42 will be located within the yoke member 50. With the handle in a normal position, the yoke member 50 will remain within the notched portion 44 and will be biased downwardly by the action of the resilient member 53 which operates upon the locking pin 51. Should the handle 41 be actuated or forced inwardly away from a vertical position, as shown in Fig. 5, the finger portion 42 will be swung arcuately upward about the pin 49 within the tapered notch portion 48. As the finger member 42 moves upwardly, the yoke member 50 is carried along

with such finger 42. As the yoke member is moved upwardly, as shown in Fig. 7, the lip portion 54 will become operatively engaged with slotted portion 47 of the stub shaft 43 and the shoulder portion 55 of the yoke 50 will become engaged with the bottom portion of the stub shaft 43.

Upon releasing the inward pressure upon the handle 41, the resilient member 53 acting upon the latching pin 51 will tend to bias the locking device 18 and the finger 42 downwardly. Should the locking pin 51 be located over an aperture 23 located within the latching plate 25, the resilient member 53 will force the locking pin 51 within the aperture 23 and the yoke 50, being operatively associated with the locking pin 51, will likewise be biased downwardly. Due to the downward action of the yoke 50, the finger 42 of the bell crank member 40 will be biased downwardly causing the handle 41 to return to a vertical position.

It is, therefore, obvious that the handle 41, swingably mounted upon the stub shaft 43, will readily operate the locking device 18 and that such handle 41 will be in a vertical position when the locking pin 51 is operatively associated with the locking plate 25.

Should the stub-shaft 43 be rotated and bell-crank operating lever 40 be slightly rotated about the stub shaft 43 as an axis, so that the operating handle 41 will be rotated slightly from the vertical position, as shown by the dotted lines in Fig. 3, the finger 42 will be in such a position that it may become operatively associated with the upper portion 50a of the yoke 50. With the bell-crank member located in such a position, it is obvious that should an inward application of force be applied to the control handle 41, the finger 42 will tend to force the yoke 50 upwardly, as hereinabove described. However, the upward movement of the yoke member 50 will be limited by the lip member 54 which will contact the stub-shaft 43 before the yoke 50 has moved such a distance as to permit the locking pin 51 to become disengaged from the locking plate 25.

The stub-shaft 43 and the operatively associated bell-crank operating lever 40 may be rotated about the stub-shaft as an axis until the operating handle 41 is substantially horizontal, as shown in Figs. 2 and 3. With the stub-shaft 43 and bell-crank operating lever 40 thus rotated, the finger 42 of the bell-crank operating lever 40 will be in contact with a side portion 50b of the yoke member 50, as shown in Fig. 3. The lip portion 54 of yoke 50 will then be substantially in contact with the stub-shaft 43 and will prohibit any upward movement of the yoke member 50. Should the operating handle 41 be actuated inwardly, the finger 42 will tend to rotate about the pin 48. However, due to the presence of the side portion 50b of the yoke member 50, the finger 42 will be prevented from rotation about the pin 49.

With the operating bell-crank member 40 in any position other than vertical, as hereinabove described, it is obvious that it will be impossible to rotate such bell-crank member about the pin 49, due to the cooperating action of the finger 42 with the portion 50a of yoke member 50 and the lip portion 54 with the stub-shaft 43, or the single cooperating action of the finger 42 with the portion 50b of yoke 50.

When the bell-crank operating lever 40 is in the vertical position, as shown in Figs. 4 and 5, the eccentrically mounted pin 37 will be in the

normal horizontal position and the clutch member 32 of the transmission 16 will be disengaged from both driving pinions 33 and 34. When the stub-shaft 43 is rotated counterclockwise substantially as shown in Fig. 2, the eccentrically mounted pin 37 will be moved vertically above such horizontal position, and the operatively associated clutch member 32 will likewise be moved upwardly. As the clutch member 32 moves upwardly, the upper protruding lip portion 36 of the clutch member 32 will engage the cooperating notched portion 39 of the upper pinion 33. Since the clutch member 32 is splined to the power shaft 19, it is obvious that with the vertical movement 10 of the clutch member 32, such clutch member 32 will provide an operative connection between the pinion 33 and the power shaft 19 and cause the wringer rolls 13 and 14 to rotate in one direction. To have the wringer rolls rotate in an opposite 20 direction, it is merely necessary to manually rotate the stub-shaft 43 and operatively associated control bell-crank member 40 in the clockwise direction. The clutch member 32 will then become operatively engaged with the pinion 34 connecting 25 such pinion with the power shaft 19 as hereinabove described.

It is, therefore, obvious that with the operating handle 41 in a vertical position, the clutch member 32 of the transmission 16 will be disengaged from both pinions 33 and 34 and the power shaft 19 will be disconnected from such pinions, and the bell-crank operating lever 40 will be in such a position that the locking device 18 may be readily operated to unlock such device and permit the 35 wringer to be swung about the vertical axis, as hereinabove described.

Likewise, it is obvious that, as the operating handle 41 and operatively associated stub-shaft 43 are rotated, the clutching member 32 of the transmission 16 will be moved from a neutral or 40 inoperative position to an operative position, and that the lip portion 54 of the yoke member 50 and the finger 42 will become operatively associated with the stub-shaft 43 and the side portion 45 50b of the yoke member 50, respectively; and, therefore, that the power shaft 19 will become operatively associated with either pinion and the locking device 18 will be in an inoperative position, as hereinabove described.

If it be desired, a die-cast cap 65 may be rigidly 50 attached to the transmission housing 15 and operatively associated with the control mechanism 17 so as to prevent the oil, located in the transmission housing, from leaking out along the operating handle 40. The cap 65 may have an oil tight 55 fit with the shoulder 45 and may have a bearing 66 within which the yoke 50 may be slidably mounted. However, it is to be understood that the cap 65 may be of any shape or size desired 60 and may be operatively associated with the control mechanism 17 in any suitable manner so as to provide an effective oil seal for such control mechanism.

Referring to Figs. 8, 9 and 10, I show a modified form of the stub-shaft 43 comprising a sleeve member 60 and a stub-shaft 43a which is journaled within the sleeve 60. The outside diameter of the sleeve 60 is substantially equal to the diameter of the stub-shaft 43. The sleeve 60 has the 70 tapered slot 48 cut therein, while the main slotted portion 47 is located within the stub-shaft 43a. The open portion comprising the main slotted portion 47 and the tapered slot portion 48 are 75 substantially equal in size and shape to the slotted

portion 46 located within the stub shaft 43 as hereinabove described.

The stub-shaft 43a comprises a shaft portion 43b and the shoulder 45. With the stub-shaft 43 located in operative engagement within the sleeve 60, the annular notched portion 44 is located between the shoulder 45 and the sleeve 60. Since the outside diameter of the sleeve 60 is substantially equal to the diameter of the stub-shaft 43, the sleeve 60 may be readily placed within the 10 aperture 39 located in the housing 15. The lip 61 integral with the sleeve 60 will then prevent the sleeve 60 from sliding out of the housing 15 and permits the sleeve 60 to be rigidly attached 15 to the housing in any suitable manner.

The bell-crank operating lever 40 may be mounted within the stub shaft 43a by inserting the pin 49 within the aperture 49a of stub shaft 43a. With the bell-crank operating lever 40 located within the stub shaft 43a, the finger 42 thereof will, as the handle 41 is actuated inwardly, move upwardly within the tapered slot 48 located within the sleeve 60. It is therefore apparent that the bell-crank operating lever 40 will readily swing about the pin 49 so long as finger 25 42 is in line with the tapered slot portion 48 of the sleeve 60.

Should the bell-crank operating lever 40 and the operatively associated stub shaft 43a be rotated substantially as shown in Fig. 10, with the 30 finger 42 located within the slotted portion 47, the finger will be prevented from rotating about the pin 49 by the presence of the sleeve 60. It is, therefore, apparent that should the operating lever 40 and operatively associated stub-shaft 43a be rotated about the stub-shaft as an axis, to even a small degree, the sleeve 60 will prohibit the inward movement of the operating handle 41 and will prevent any binding of parts 35 between the operating mechanism 17 and the 40 locking device 18.

A flange 70, shown in Fig. 11, may be associated with the transmission housing 15 as a further modification for preventing the inward movement of the operating handle 41, except 45 when such handle is in a vertical position. The flange 70 may be cast integral with the housing 15 or may be a separate piece rigidly attached thereto. The flange will extend outwardly in such a manner that the upper inner surface of 50 the handle 41 will contact the flange with a slight inward movement of such handle. The handle 41 will then be prevented from any further inward movement, and, therefore, when in such a 55 position, will not be capable of operating the locking device 18.

A notch 71 may be located within the flange 70 at a lower central position to permit the handle 41 to be moved inwardly, when such handle is in a substantially vertical position. The notch 71 should be slightly larger than the width 60 of handle 41 to permit easy access of such handle therein. By so limiting the width of the notch 71, the handle 41 will be prohibited from any inward movement except when it is directly in line with such notch, or in substantially 65 a vertical position.

It is, therefore, obvious that the flange 70 with notch 71 will prevent the operation of the locking device 18 except when the operating handle 70 41 is in a vertical position, and, accordingly prevent the operation of the locking device 18 except when the power shaft 19 is disconnected from wringer rolls 13 and 14.

In operating a wringer embodying my inven- 75

tion, in which the wringer is controlled by means of a single operating lever 41, as hereinabove described, the operator may rotate the lever 41 about the stub-shaft 43 as an axis from one horizontal position to an opposite horizontal position to reverse the wringer from one direction of operation to the other. As the operator makes this change, the wringer remains locked in its set position due to the cooperation of the locking pin 51 and the locking plate 25. If the operator should wish to swing the wringer from one position to another, it becomes necessary to move the operating lever 41 to a vertical position, where, as hereinabove described, the wringer 11 may be disconnected from the power shaft 19.

With the operating lever 41 in the vertical position, it is merely necessary to push such lever inwardly, whereupon the locking pin 51 will become disengaged from the locking plate 25, in a manner hereinabove described, permitting the wringer to be swung about the power shaft 19 as an axis. When the wringer has been swung into the desired position, the operator merely withdraws the pressure from the operating lever 41, permitting the resilient spring 53 to bias the locking pin 51 downwardly. Should the wringer be slightly away from a predetermined adjustable position, the locking pin 51 will rest upon the locking plate 25. The wringer may then be moved slightly until the snout 51 of locking pin 51 becomes engaged within the aperture 23. It is to be understood that the operating lever 41 can be moved from the vertical position only when the locking pin 51 is operatively engaged with the locking plate 25, as hereinabove described. With the wringer located in its newly adjusted position, the operator may then rotate the operating handle 41 in whichever direction desired about the stub shaft 43 as an axis to engage the wringer rolls with the power shaft.

It is, therefore, obvious that the operating mechanism embodying my invention may selectively operate either the transmission or the locking device and will permit the transmission to be in a neutral position without unlocking the wringer. However, it is to be understood that the locking device can be operated only when the transmission is in a neutral position, or, in other words, when the operating handle is in a vertical position.

Various modifications may be made in the device embodying my invention without departing from the spirit and scope thereof, and I desire, therefore, that only such limitations shall be placed thereon as are imposed by the prior art and by the appended claims.

I claim as my invention:

1. A wringer adapted for adjustment to different working positions, a roll-driving and reversing mechanism including a clutch, locking means for holding said wringer in its adjusted positions, a rotatably mounted hollow stub-shaft having means thereon for operating the clutch, an operating member comprising a handle and a finger swingably mounted in a substantially vertical plane within the hollow stub-shaft, means comprising the finger for actuating the locking means when the handle is biased inwardly and for rotating the stub-shaft as the handle is relatively biased, and means for preventing the actuation of the locking means except when the clutch is in a neutral position.

2. In a wringer adapted for adjustment to different working positions, a roll-driving and reversing mechanism including a clutch, locking

means including a yoke member and a locking pin for holding said wringer in its adjusted position, a rotatably mounted stub-shaft having means thereon for operating the clutch, an operating member swingably mounted within the stub-shaft, said yoke member operatively associated with the stub-shaft and the operating member, and means comprising the operating member for selectively actuating either the clutch or the locking means.

3. In a wringer adapted for adjustment to different working positions, a roll-driving and reversing mechanism including a clutch, locking means including a yoke member and a locking pin for holding said wringer in its adjusted position, a rotatably mounted stub-shaft having means thereon for operating the clutch when said stub-shaft is rotated, an operating member comprising a handle and a finger swingably mounted within the stub-shaft, said yoke member operatively associated with the stub-shaft and the finger, means comprising the finger for actuating the locking device when the handle is biased inwardly and for rotating the stub-shaft as the handle is rotatively biased, and means comprising the yoke for preventing the actuation of the locking means except when the clutch is in a neutral position.

4. In combination, a wringer mounted for adjustment in different working positions, a roll-driving and reversing mechanism including a clutch, locking means comprising a yoke member operatively associated with said clutch operating means and a locking member for holding the wringer in one of its adjusted positions, and interlocking means including said yoke for actuating the locking member when said clutch is in a neutral position.

5. In combination, a wringer mounted for adjustment in different working positions, a roll-driving and reversing mechanism including a clutch, a stub-shaft having means thereon for operating the clutch, locking means comprising a yoke member operatively associated with said stub-shaft and a locking member for holding the wringer in one of its adjusted positions, an operating member operatively associated with the stub-shaft and the yoke member for selectively actuating either the clutch or the locking member, and interlocking means including said yoke member for preventing the actuation of the locking member except when the clutch is in a neutral position.

6. In a wringer adapted for adjustment to different working positions, a roll-driving and reversing mechanism including a clutch, a locking member for holding said wringer in its adjusted position, a hollow stub-shaft having means thereon for operating the clutch, a bell-crank lever comprising an operating handle and a finger, said finger being operatively associated with said stub-shaft within the hollow thereof and with the locking member, and means comprising said operating handle for selectively actuating either the clutch or the locking member.

7. In a wringer adapted for adjustment to different working positions, a roll-driving and reversing mechanism including a clutch, a locking device comprising a yoke member and a locking pin for holding said wringer in its adjusted position, a slotted stub-shaft having means thereon for operating the clutch, a bell-crank member comprising an operating handle and a finger, said finger being operatively associated with said stub-shaft within the slot thereof and with the yoke

member, and means comprising said operating handle for selectively actuating either the clutch or the locking device.

8. In a wringer adapted for adjustment to different working positions, a roll-driving and reversing mechanism including a clutch, a locking device comprising a yoke member and a locking pin for holding said wringer in its adjusted position, a stub-shaft having a slot and having means thereon for operating the clutch, a bell-crank member comprising an operating handle and a finger, said finger being operatively associated with said slot and with the yoke member, means comprising said operating handle for selectively actuating either the clutch or the locking device, and means comprising the yoke member for preventing the actuation of the locking means except when the clutch is in a neutral position.

20 9. In combination, a structure mounted for adjustment in different working positions around a substantially vertical axis, a reversing mechanism including a clutch operable along said axis, means for operating said clutch, locking means operatively associated with said clutch-operating means and comprising a locking member for holding said structure in one of its adjusted positions, manually operable means rotatable around a substantially horizontal axis for actuating said clutch from a neutral to a working position, said manually operable means being rotatable around a second substantially horizontal axis for actuating said locking member when said clutch is in a neutral position.

35 10. In combination, a structure mounted for adjustment in different working positions around a substantially vertical axis, a reversing mechanism including a clutch operable along said axis, means for operating said clutch, locking means operatively associated with said clutch-operating means and comprising a locking member for holding said structure in one of its adjusted posi-

tions, manually operable means rotatable around a substantially horizontal axis for actuating said clutch from a neutral to a working position, said manually operable means being rotatable around a second substantially horizontal axis at substantially right angles to the first-named horizontal axis for actuating said locking member when said clutch is in a vertical position.

5 11. In combination, a structure mounted for adjustment in different working positions around a substantially vertical axis, a reversing mechanism including a clutch operable along said axis, means for operating said clutch, locking means operatively associated with said clutch-operating means and comprising a locking member for holding said structure in one of its adjusted positions, an operating device pivoted at substantially right angles to said axis and adapted when moved in one direction around the pivot to correspondingly move said locking member when said clutch is in a neutral position; said operating device when moved in another direction actuating said clutch from a neutral to a working position.

15 25 12. In combination, a structure mounted for adjustment in different working positions around a substantially vertical axis, a reversing mechanism including a clutch operable along said axis, means for operating said clutch, locking means operatively associated with said clutch-operating means and comprising a locking member for holding said structure in one of its adjusted positions, an operating device pivoted at substantially right angles to said axis and adapted when moved in one direction around the pivot to correspondingly move said locking member when said clutch is in a neutral position; said operating device when moved about an axis at substantially right angles to the first-named axis and also to said pivot actuating said clutch from a neutral to a working position.

30 35 40 FLOYD S. WHEELER.
